UNITED STATES PATENT OFFICE.

JOHN JENKS, OF SAN DIEGO, CALIFORNIA.

HANGER FOR SCREENS.

1,012,085.

Specification of Letters Patent. Patented Dec. 19, 1911.

Application filed January 13, 1910, Serial No. 537,946. Renewed May 1, 1911. Serial No. 624,470.

To all whom it may concern:

Be it known that I, JOHN JENKS, a citizen of the United States of America, residing at San Diego, in the county of San Diego and State of California, have invented certain new and useful Improvements in Hangers for Screens, of which the following is a specification.

This invention relates to hangers for screens, the object of the invention being to provide a hanger so constructed that the screen will be hingedly mounted for bodily swinging movement or for vertical sliding movement, the hanger being adapted to frictionally grasp the screen frame and maintain said frame in any position to which it may be adjusted.

Further objects and advantages of the invention will be set forth in the detailed description which now follows:

In the accompanying drawing, Figure 1 is an elevation of a window having the invention applied thereto, Fig. 2 is a vertical section through said window, Fig. 3 is a front elevation of one of the hangers, and, Fig. 4 is a side elevation of said hanger.

Like numerals designate corresponding parts in all of the figures of the drawing.

Referring to the drawing, it will be seen that each of the hangers comprises a back plate 5 having screw holes 6 and 7 formed in its opposite upper corners. Transversely projecting side plates 8 are bent from the back plate 5, these side plates 8 having extensions 9 integral therewith and located at the bottom of the hanger. A downwardly extending cut or slit 10 is formed between each of the side plates 8, and the back plate 5, and the upper portion 11 of each of the side plates is inwardly bowed to form a spring clamp, it being understood that the screen frame slides between and is gripped by these spring clamps. The purpose of providing two screw holes in each of the hangers is to render each of the hangers either a right or a left hand hanger. It is to be understood however, that in use only one screw is employed to secure each of the hangers in place, said screw serving to rigidly or pivotally connect said hanger to the window frame.

In Figs. 1 and 2, the window frame is designated by the reference numeral 12. A screw 13 (see Fig. 2) is passed through the inner screw opening of the hangers, indicated in a general way at 14 and 15. The

screen frame 16 is slidably disposed in these hangers and it is apparent that the screen may be lifted by sliding the frame through the hangers, or that it may be swung bodily with the hangers upon the pivots provided by the screws 13, only one of said screws being illustrated. If desired, a hook and eye 17 may be employed to lock the screen against either vertical sliding movement or bodily swinging movement.

Stop screws 18, carried by the screen frame stop against the curved recess in extensions 9 of the hangers, to prevent it from being accidentally withdrawn from the hangers when the hangers are swung upon the pivot screws 13. These screws 18 not only prevent the accidental withdrawal of the screen frame from the hangers, but they also determine the extent to which the screen frame may be lowered and therefore maintain it at the proper height to permit of the swinging movement above referred to, without danger of the lower edge of the screen striking against the window sill 19.

While for the sake of clearness in illustration, I have illustrated the upper edge of the screen frame as lying below the pivot screws 13, it is apparent that if desired, this screen frame may be so made that its upper edge may lie in front of the screw 13, to thereby prevent the removal of said screws.

While I have illustrated the hangers and the screen mounted upon the inner side of the window, it is apparent that these parts may be mounted upon the outer side of the window and swung outwardly therefrom if desired, or used on a screen covering the entire window without departure from the invention.

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.

Having described my invention, what I claim is:

1. The combination with a window frame, of a pair of screen hangers secured thereto, one at each side thereof, each of said hangers comprising a back plate, a pivot screw

which pierces said back plate and hingedly connects it to said window frame, transversely extending side walls projecting from said back plates, the upper portion of each of the side walls being bent to form bowed, resilient, friction members, a screen frame slidably disposed between said friction members, stop members carried by the screen frame, and extensions formed upon 10 the side walls with which said stop members engage, to limit the downward movement of the screen frame with relation to the hangers.

2. The combination with a window frame, 15 of a pair of screen hangers secured thereto, one at each side thereof, each of said hangers comprising a back plate, a pivot screw which pierces said back plate and hingedly connects it to said window frame, trans- 20 versely extending, side walls projecting from said back plates, the upper portion of each of the side walls being bent to form bowed, resilient, friction members, a screen frame slidably disposed between said friction members, stop members carried by the screen frame, extensions formed upon the 25 side walls with which said stop members engage, to limit the downward movement

of the screen frame with relation to the hangers, and means for locking the lower 30 edge of the screen frame to the window sill substantially as shown and described.

3. A hanger for screen frames, comprising a back plate having an opening formed therein for a pivot screw, said opening being disposed at one side of the center line of said back plate, side walls lying substantially at right angles to said back plate, said side walls being cut to form a plurality of resilient members adapted to frictionally 40 engage a screen frame and a member passing through the opening in said back plate to eccentrically and pivotally mount the hanger upon a window frame.

4. The combination with a pair of swing- 45 ingly mounted hangers, of spring clamps carried thereby and adapted to frictionally engage a screen frame, and a screen frame slidably disposed in said hangers.

In testimony whereof I affix my signature in presence of two witnesses.

JOHN JENKS.
